CLAIM

The ornamental design for a measuring tape, as shown and described

DESCRIPTION

FIGS. 1-6 are top views of the measuring tape of my design, in which the scale of inch markings and fractions thereof is doubled from the conventional scale of inch markings and fractions thereof of ordinary measuring tape;

FIG. 7 is a left side view of the measuring tape;

FIG. 8 is a right side view of the measuring tape;

FIG. 9 is a bottom view of the measuring tape;

FIG. 10 is a first end view of the measuring tape; and FIG. 11 is a second end view of the measuring tape.

1 Claim, 2 Drawing - Sheet 1
